UNITED STATES PATENT OFFICE.

WARREN F. FARAGHER AND WILLIAM ARTHUR GRUSE, OF PITTSBURGH, PENNSYLVANIA, ASSIGNORS TO GULF REFINING COMPANY, OF PITTSBURGH, PENNSYLVANIA, A CORPORATION OF TEXAS.

PROCESS FOR CRACKING HYDROCARBON OILS.

Application filed January 15, 1921. Serial No. 437,480.

This invention relates to an improved method for making motor fuel or gasoline by cracking heavy hydrocarbon oils, such as the higher boiling fractions and residual oils of petroleum or shale oil distillation, etc.

When such oils are subjected to cracking in an externally heated still, serious difficulties are encountered in large-scale operations, due to the deposition of a carbonaceous solid, commonly referred to as "carbon," on the heated walls of the still. Such a deposit of "carbon" interferes with the conduction of heat into the oil, and results in increased cost of gasoline-production, owing to the necessity of cleaning the "carbon" from the still walls and the loss of operating time during such cleaning operations; while the life of the still wall is comparatively short due to the rapid burning out of the iron in contact with "carbon." These difficulties are encountered in externally heated stills of various kinds, including stills of the water-tube boiler type, where the oil is heated in its passage through a series of tubes.

Attempts have been made to overcome the difficulties mentioned by providing stirrers in the still for agitation of the oil, and, in stills of the water-tube boiler type, it has been proposed in oil cracking operations to provide mechanical stirrers or propellers for increasing the circulation through the heated tubes (a practice well known in steam boiler operations); but such mechanical stirrers and propellers are open to the objection that they require stuffing boxes which must operate against highly heated oil and heated oil vapors at high pressures.

The present invention relates to an improved method for cracking oils, in which the cracking operation is carried out in a still of the water-tube boiler type, and in which a positive and efficient circulation of the oil through the heated tubes is effected without mechanical agitators or propellers, and with avoidance or substantial avoidance of objectionable deposition of "carbon" in the heated tubes. This circulation of the oil through the tubes is effected, according to the present invention, by the introduction of a jet or a series of jets of gas, or by the internal generation of gas, acting on the "air-lift" principle, to bring about a rapid

and effective circulation of the oil through the heated tubes.

The gases used for effecting the circulation of the oil, according to the present invention, may with advantage be the fixed gases formed during the cracking operation, or the mixed gases and vapors taken from the vapor line of the still and recirculated; but other appropriate gases can be used, such as natural gas or casing-head gas, or other gaseous materials, such as steam, which have no objectionable effect upon the cracking operation. The introduction or reintroduction of these gases into the still has the further advantage of promoting the regular removal of the lower boiling constituents resulting from the cracking operation as they are formed, thus preventing their remaining in the still to undergo further objectionable cracking or decomposition. When a portion of the gases or vapors produced by the cracking operation is recirculated through the still, these gases may be freed from a part or the whole of the readily condensable constituents before recirculation, or the hot gases and vapors from the still can be recirculated with the removal therefrom of only the higher boiling constituents.

The invention will be further illustrated and described in connection with the accompanying drawings, which show, in a somewhat conventional and diagrammatic manner, different forms of apparatus adapted for the practice of the process of the invention.

In the accompanying drawings,

Fig. 1 shows one form of apparatus embodying the invention in vertical longitudinal section and with parts in elevation; and

Fig. 2 is an end view of the apparatus of Fig. 1, with the furnace structure removed.

In the apparatus illustrated, the still is of the water-tube boiler type and is made up of the upper longitudinal drum 1, the two lower transverse drums 2 and 4 with vertical connecting legs or tubes 3 and 5 respectively, and with a series of tubes 6 connecting the two lower transverse drums and suitably arranged to be heated in a furnace chamber 7.

The upper longitudinal drum 1 has a suitable dephlegmator 8 and a vapor pipe 9 leading therefrom to the condenser 17. Oil is supplied to the upper drum from an oil

supply tank 10 through a feed tube 11. The oil level is automatically maintained in the oil supply tank 10 in any suitable manner, as by introducing the oil through the inlet 12 by means of a pump (not shown) regulated by the oil level in the receptacle 10. A vapor pipe 13 connects the vapor space of the oil supply tank 10 with the vapor pipe 9 so that the same pressure will be maintained in the oil supply tank as in the still and so that oil will automatically flow from the supply tank to the still to maintain a constant level therein. An outlet for the residue is indicated at the bottom of the still at 15.

In the shorter depending legs 5 there are provided foot-pieces 14 through which gas is introduced from pipes 16. The gas is blown in through the foot-pieces 14 so as to cause a rapid and positive flow of oil up through these legs. This, in turn, causes a rapid and effective circulation of oil through the heated tubes 6, the oil circulating downwardly through the leg 3 to the transverse drum 2, thence through the heated tubes to the drum 4 and upwardly through the legs 5, and being repeatedly recirculated in this way. In this way the oil is kept rapidly circulating through the tubes 6 and deposition of "carbon" in these tubes, which is the chief source of trouble in stills of this type, is avoided or minimized. The tar and heavier sediment collect at the bottom of the transverse drum 2 and are discharged through the outlet 15.

The construction and arrangement, as well as the number, of the tubes, and of the depending legs, joining the upper longitudinal drum with the two lower transverse drums, can be varied. The construction and arrangement should preferably be such as to give a substantially uniform distribution and flow of the oil through the tubes. This uniformity of distribution and of flow can be promoted, for example, by providing a plurality of depending legs, such as are shown at 5. The provision of a plurality of such legs, each with a gas inlet pipe for securing an "air-lift" action therein, permits the regulation of the flow through the tubes, to a greater or less extent, by varying the gas introduced into the different legs. For example, if an increased velocity of flow is produced in the outer legs 5, this will tend to increase the flow of oil through the outer pipes, thus preventing or reducing the tendency for the oil to flow more slowly in the outer tubes than in the centrally arranged tubes.

In the operation of the apparatus and the carrying out of the oil cracking process, the oil is heated by its passage through the tubes 6 and pressure is maintained in the still by placing a suitable regulating valve 18 in the vapor line, preferably beyond the con-

denser as shown, thereby confining the vapors and fixed gases developed by the process and maintaining the proper pressure for the cracking operation. The oil inflow is supplied from the oil reservoir 10 in which the oil level is maintained in any suitable manner, as by a pump controlled by an automatic float device (not shown). There are no stuffing boxes or moving parts of the still, but rapid and effective circulation of the oil through the heating tubes is nevertheless effected by the introduction of gas in the manner described.

The operation is continuous and can be continued for long periods of time, the residuum accumulating and being removed through the outlet 15 and the oil being automatically supplied to maintain a constant level within the still. The rapid circulation of the oil within the still promotes uniformity of heating and of cracking, thus avoiding or minimizing local overheating. The continuous rapid circulation of the oil through the heated tubes causes the oil in contact with the heated walls of the device to be continuously swept or scoured off so that the formation of a "dead layer" of oil is prevented, with resulting prevention or substantial prevention of the heating of such a layer to objectionably high temperature.

It is one advantage of the invention that the use of moving mechanism is avoided, so that stuffing boxes are avoided, and so that all connections of the still may be welded and made gas-tight.

The introduction of a current or currents of gas not only serves to insure effective agitation and circulation of the oil, but it promotes the regular removal of the lower-boiling constituents resulting from the cracking operation as they are formed, and prevents their remaining in the still to undergo further decomposition. The excess gas, resulting from the cracking operation, can be discharged from the still in any of the usual ways, while the gas that is to be recirculated through the still can be freed from undesired high boiling constituents in a suitable dephlegmator, and from the desired condensable constituents in a suitable condenser, and can then be passed through a pump or gas-booster 19 and sufficiently increased in pressure to be used again.

By drawing off the admixed fixed gases and vapors, from the vapor pipe 9 at still pressure and at substantially still temperature through connection 20, and by recirculating and reintroducing these gases for bringing about the circulation of the oil, the amount of work required for compression of the gases is reduced and the sensible heat of the gases can be sufficiently conserved so that they exert no objectionable cooling effect when reintroduced.

In the apparatus illustrated the heated

tubes are made slightly curved so as to avoid strains set up by expansion and contraction.

The oil supply to the still may be pre-heated to a greater or less extent, preferably 5 to such a degree as to vaporize and remove any water present therein before the oil is supplied to the still. By preheating the oil in this way, the preheating effect required from the tubes will be correspondingly reduced. A part of the heat necessary for the preheating can be supplied by means of a heat interchanger through which the still "bottoms" are discharged; while a part of the preheating may be effected by bringing 10 the oil into heat interchanging relation with the hot vapors from the still, for example, by passing the oil through the condenser for the vapors of distillation and cracking, or through one or more of the series of condensers where such a series is used. The preheating effect thus secured may be supplemented, if desired, by further preheating of the oil in any suitable manner. Owing to 15 the rapid and continuous circulation of the oil through the heated tubes, uniformity of heating is promoted, and the resulting cracking operation is of a more uniform character and results in an increased yield of gasoline and lower gas and coke losses, and hence 20 an increased capacity or increased yields for a given size still, as compared with a still which is not provided with means for effecting such circulation.

It will, of course, be understood that the 25 manner of introducing the gases for bringing about and promoting the circulation can be varied, for example, the gas jets can be varied in number and arrangement, as well as in shape and location, provided only that 30 they serve as means for effecting the constant and substantially uniform circulation of the oil through the heated tubes.

In illustrating the apparatus in the accompanying drawings, we have omitted the 45 heat insulation or lagging of the still, connecting pipes, etc. but it will be understood that, in practice, suitable heat insulation will be provided to avoid objectionable losses from all exposed parts of the still and of the 50 system which become heated.

It will be understood that the stills will, in practice, be provided with suitable temperature, pressure and level indicating devices (not shown) as well as means for producing and maintaining within the still the necessary temperature and pressure conditions for the cracking operation. The cracking operation may thus be carried out under a regulated pressure, for example, of 60 between 60 and 500 pounds per square inch, and preferably in the neighborhood of 75 to 150 pounds per square inch, depending upon the nature of the oil to be cracked and the products desired.

65 In referring to the cracking of "oil" in

the present specification and claims, we intend to include the treatment of various hydrocarbon oils, and more particularly the treatment of higher boiling fractions and residual oils of petroleum or shale oil distillation, for the production of motor fuel or gasoline; but other oils, such as lignite or coal tar or tar oils, etc., can be similarly treated; and we include all such material within the term "oil", as used in the accompanying claims.

70 It is to be understood that a plurality of stills of the designs disclosed in this specification may be arranged in series and the oil to be cracked passed through them consecutively.

We claim:

1. The method of cracking oils in a pressure still, which comprises maintaining a pool of oil and circulating oil from the pool 85 downwardly to one end of heating tubes, thence through the heating tubes, and upwardly back from the other end of the heating tubes to the said pool, heating the oil to a cracking temperature in the said heating tubes, and promoting circulation of the oil 90 through the heating tubes by introducing a current or currents of gas, acting on the "air-lift" principle, into the oil at a point in its passage upwardly between the heating 95 tubes and said pool.

2. The method of cracking oils in a pressure still, which comprises circulating the oil from and to a drum through tubes heated to a cracking temperature and promoting the circulation of oil through the heated tubes of the still by introducing a current or currents of gas, acting on the "air-lift" principle, into the oil at a point in its passage 100 upwardly between the tubes and the drum. 105

3. The method of cracking oils in a pressure still, which comprises circulating the oil from and to a drum through tubes heated to a cracking temperature and promoting the circulation of oil through the heated 110 tubes of the still by introducing a current or currents of gas from the still, acting on the "air-lift" principle, into the oil at a point in its passage upwardly between the tubes and the drum. 115

4. The method of cracking oils in a pressure still, which comprises circulating the oil from and to a drum through tubes heated to a cracking temperature and promoting the circulation of oil through the heated tubes of the still by introducing a current or currents of gas and vapor from the still and at substantially the still temperature, acting on the "air-lift" principle, into the oil at a point in its passage upwardly between the tubes and the drum. 120 125

5. The process of pyrogenetically distilling lower boiling point hydrocarbon oils from higher boiling point hydrocarbons which consists in maintaining a bulk supply 130

4
thereof under pressure, withdrawing oil therefrom, passing it in a stream through a heated zone and returning it to said bulk supply, and injecting a gaseous medium into it in the direction of its flow in its passage between the heated zone and the bulk supply.

5 6. The process of pyrogenetically distilling lower boiling point hydrocarbon oils
10 from higher boiling point hydrocarbons which consists in maintaining a bulk supply thereof under pressure, withdrawing oil

therefrom, passing it in an upwardly directed stream thru a heated zone and back to the bulk supply, whereby circulation of ¹⁵ the oil is thermally maintained, and injecting steam upwardly into the oil in its passage between the heated zone and the bulk supply.

In testimony whereof we affix our signatures.
